CLAIM

The ornamental design for blacking members in a smoke detector chamber, as shown and described.

DESCRIPTION

FIG. 1 is bottom view;

FIG. 2 is a side view;

FIG. 3 is a cross-sectional view taken along the lines 3-3 of FIG. 1;

FIG. 4 is top;

FIG. 5 is an alternate side view;

FIG. 6 is an alternate bottom; and,

FIG. 7 is an perspective view.

The broken lines in the drawings illustrate portions of the blocking members that form no part of the claimed design. Any unshaded regions bounded by broken lines in the drawings illustrate the bounds of the claim and form no part thereof. Non-oblique line shading represents contour and not surface ornamentation.
